UNITED STATES PATENT OFFICE.

JOHN KRASNODEMSKI, OF WAUSAU, WISCONSIN, ASSIGNOR OF FIVE ONE-HUNDREDTHS
TO JOHN GORSKI, OF WAUSAU, WISCONSIN.

COMBINED SWORD AND PISTOL.

1,238,527.

Specification of Letters Patent. Patented Aug. 28, 1917.

Application filed November 1, 1916. Serial No. 128,958.

To all whom it may concern:

Be it known that I, JOHN KRASNODEMSKI, a citizen of the United States, residing at Wausau, in the county of Marathon and State of Wisconsin, have invented certain new and useful Improvements in Combined Swords and Pistols, of which the following is a specification, reference being had to the accompanying drawings.

10 This invention relates to arms and particularly to combined fire arms and swords.

The general object of the invention is to provide a pistol in connection with a sword, the pistol being so disposed that it may be 15 readily operated when the sword is used but will not interfere with the use of the sword itself.

One of the objects of the invention is to so construct a combined sword and pistol 20 that the handle of the sword is not obstructed in any way by the addition of the pistol and that the weight of the sword is not appreciably increased by the addition of the pistol mechanism to the hilt of the sword.

25 A further object of the invention is to provide a magazine pistol in connection with a sword, the magazine being so constructed that clips containing a predetermined number of cartridges may be used 30 in connection therewith.

Still another object of the invention is to provide a plurality of safety locks which will prevent the pistol from being discharged in ordinary use or carriage of the 35 sword and only at the will of the operator.

A further object of the invention is to so construct the mechanism that when the loaded magazine or clip is inserted in its holder, it is impossible to discharge any of 40 the cartridges until the mechanism has been initially set and the first shell shifted into the firing chamber.

A further object in this connection is to provide thereafter for the automatic cocking or retraction of the firing pin by the recoil of the charge.

A further object is to provide means for normally preventing the firing of the cartridge in the firing chamber, consisting of 50 a member mounted upon the hilt normally

held in an operative position, preventing the forward movement of the firing pin, but which when turned over and held by the grasp of the hand on the hilt will permit the firing of the cartridge by pressure 55 upon the trigger.

Still another object is to provide an additional safety device, preventing the firing of the cartridge when the sword is in its scabbard.

Still another object is to prevent the discharge of the cartridge unless it fits firmly in the firing chamber and to provide a mechanism so constructed that if the last cartridge from a clip is left in the firing 65 chamber and a loaded clip is put in place in the magazine, firing can continue without again initially setting the firing mechanism.

Other objects have to do with the details 70 of construction and improvement of certain parts of the mechanism and will be hereafter more fully stated.

One form of my invention is illustrated in the accompanying drawings, wherein— 75

Figure 1 is a side elevation of a sword hilt and part of the blade, the sword being constructed in accordance with my invention;

Fig. 2 is a side elevation of the sword hilt 80 and blade showing the trigger housing removed and the housing for the trigger lock in section;

Fig. 3 is a longitudinal sectional view through the hilt of the sword showing the 85 firing pin retracted but locked from actuation;

Fig. 4 is a longitudinal section through the magazine, the hilt of the sword, the barrel, the safety lock, and the trigger operating mechanism, this figure showing the firing pin in its released position;

Fig. 5 is a like view to Fig. 4, the mechanism, however, being shown in elevation, showing the firing pin and the breech block 95 retracted, and a cartridge just being shifted into the firing chamber;

Fig. 6 is a fragmentary side elevation of a portion of the sword and a portion of the hilt showing the cartridge ejecting open- 100

- ing and door for the same, the view being taken on the opposite side of the sword from that shown in Fig. 2;
- 5 Fig. 7 is a perspective view of the sleeve which carries the breech block;
- Fig. 8 is an under side plan view of the sleeve shown in Fig. 7;
- Fig. 9 is a cross section on the line 9—9 of Fig. 4;
- 10 Fig. 10 is a perspective view of the bed or cradle which supports a portion of the operating mechanism, the barrel and the upper end of the magazine;
- Fig. 11 is a perspective view of the safety lock operating mechanism;
- 15 Fig. 12 is a sectional view on the line 12—12 of Fig. 11;
- Fig. 13 is a section on the line 13—13 of Fig. 11;
- 20 Fig. 14 is a perspective view of the firing pin;
- Fig. 15 is a perspective view of the sear and associated parts, the several parts thereof being separated;
- 25 Fig. 16 is a top plan view of the sear;
- Fig. 17 is a perspective view of the breech block retracting rod and its tubular guide;
- Fig. 18 is a cross section on the line 18—18 of Fig. 17;
- 30 Fig. 19 is a perspective view of the yoke for retracting the rod 45;
- Fig. 20 is a perspective view of the breech block retracting member.
- Fig. 21 is an under side plan view with 35 the magazine and frame in section and the rear end of the guard in section;
- Fig. 22 is a longitudinal sectional view of the breech block and its slide 18 showing the same in its forward position and the 40 lock 79 raised and in its operative position;
- Fig. 23 is a like view to Fig. 22 but showing the slide shifted forward and the lock 79 in its inoperative position;
- Fig. 24 is a fragmentary longitudinal sectional view of the rear end of the barrel and a portion of the breech block showing the retractor;
- 45 Figs. 25, 26, 27 and 28 are diagrammatic views showing the operation of the mechanism, Fig. 25 showing the position of the parts before a cartridge has passed into the barrel, Fig. 26 showing the slide and firing pin retracted and the firing pin held, a cartridge being shifted into the firing chamber, 50 Fig. 27 showing the parts with the slide shifted to close the breech but the firing pin still retracted, and Fig. 28 is a like view to Fig. 26 but showing the old cartridge being ejected by the fresh cartridge entering the 55 firing chamber.
- 60 The sword is of the usual form and consists of the blade 10, the hilt 11 and the guard 12. The blade is disposed to one side of the axial longitudinal plane of the hilt 65 in order to provide for the barrel, pistol,

the magazine, and the firing and locking mechanism. The barrel is disposed parallel and adjacent to the side of the blade and preferably to the left hand side of the blade. The hilt 11 is hollow and may be formed of 70 any number of sections, though as illustrated it is formed of the two sections *a* and *b* on each side intermediate the longitudinally extending sections, the side face of the hilt, as illustrated in Fig. 1, being provided with 75 the wooden inserts *c* whereby to provide for a proper grip on the handle of the sword. It is to be understood that this is purely 80 illustrative as the hilt of the sword may be constructed in any suitable manner and of any suitable material and have any other desired form than that illustrated, it being only necessary that the hilt be hollow to contain the mechanism to be hereafter described. The hilt is extended forward beyond the guard to form a housing 13 and within this housing is disposed the barrel 14 which at its rear has a lug 15. On its under side, the barrel is formed with ribs 16 (see Fig. 10), these ribs engaging with the 85 ribs on a bed or cradle piece designated generally 17.

Surrounding the upper portion of the barrel 14 and disposed between the barrel and the upper wall of the hilt 11 and its extension 13 is an approximately semi-cylindrical slide 18 (see Figs. 7, 8 and 9). This slide has a relatively long rear wall 19 which extends downward below the upper portion of the slide and forms a hollow breech block 100 20, the forward end of the breech block being perforated. At the forward end of the guard is formed a magazine receiving frame constituted by the forward wall 21 of the guard and a parallel wall 22 and the side walls 23 (see Figs. 2 and 3). The lower end of the magazine frame is open for the reception of the magazine clip 24. This is rectangular in cross section, has a sliding fit in the frame, and is open at its upper end. Disposed therein is a follower 25 (see Fig. 4) urged upward by a spring 26. The lower end of the clip is closed by a wall 27, having an outwardly projecting rib 28 which limits the upward movement of the magazine clip and the clip is held in place by a pivoted dog 29 having a knurled head 30 which overlaps the lower end of the clip and is urged into this position by a spring 31. This dog is pivoted in a recess formed 115 in the inner face of the wall 21, as shown most clearly in Fig. 4. By shifting this dog rearward, the clip may be readily withdrawn from the magazine frame and a new clip inserted. When the clip is in position its upper end is disposed immediately beneath the breech block 20 and the cartridges are discharged into the chamber 31 formed by the retracted breech block, the slide or sleeve 18 and the rear of the barrel 14, as shown 120 125 130

in Fig. 5. Slidely mounted in the thickened rear wall 19 of the slide 18 is a firing pin 32 (see Fig. 14) which has a pointed head 33, adapted to project through the perforation in the breech block, and a cylindrical hollow barrel 32 and rearward extension 34, the extremity of which extension is formed with a detent 35. The barrel 32 at its rear end is formed with a downwardly extending detent tooth 36. The extension or rod 34 passes through an apertured guide lug 37 on the rear end of the bed plate 17, (see Fig. 10) this lug 37 constituting an abutment for a spring 38 which surrounds the rod 34 and bears at its forward end against the head 33. Thus the slide 18 and the firing pin and its rod 34 have independent sliding movement.

Adjacent the rear end of the hilt is a member 39 constituting a transverse wall or abutment and formed on its upper portion with an open ended chamber 40 in which is mounted a pivoted latch or detent 41, this latch being U-shaped in cross section, as shown most clearly in Fig. 13. This latch has a detent tooth 42 which coacts with the toothed end of the rod 34 when the firing pin is retracted, as seen in Fig. 5. The latch is urged downward into its operative position by a spring 43, as shown in Fig. 3, which spring bears against a laterally projecting pin 44 on the latch. When the latch is engaged with the extremity of the firing pin 34 it will hold the firing pin in its retracted position until the firing pin is released by the trigger mechanism which in turn releases the detent or latch 41 from its engagement with the firing pin, permitting the spring 38 to urge the firing pin forward from its rearward position against the cartridge. The slide 18 and the firing pin, which is connected with it, are retracted by means of a pull rod 45 which at its forward end is formed with a lug 46 and at its rear is formed with a head 47 connected by a screw 48 to a transversely extending cross bar 49 forming a yoke having longitudinally extending side rods 50 (see Fig. 19). These rods at their rear ends are toothed as 51 and operate in guide ways 52 formed in the side wall of the hilt at the butt thereof, the guide ways being normally covered by plates 53 held to the body of the hilt by screws. The ends of the cross bar 49 project beyond the rods 50 and are knurled to form finger grips. The toothed faces 51 of the rods 50 and the knurled extremities of the cross bar 49 permit a firm hold to be taken of the yoke between the finger and thumb 60 of the operator so that the yoke may be withdrawn against the force of a spring which tends to urge the rod 45 forward, this spring being designated 54 and illustrated in Fig. 4. The rod 45, as before stated, at its forward end is formed with an upwardly

extending lug (see Fig. 17) and the rod operates through a tubular guide 55, the forward portion of which is slotted at 56 for the passage of the lug 46. The rear end of the tubular guide 55 passes through the member 39 and into a block or cross bar 57, as shown in Fig. 4. The rod 45 at its forward end passes through a head 59 having a longitudinally extending shank 60 (see Fig. 7), this head 59 being formed with a circular passage 61 through which the guide 55 passes. This circular opening or passage 61 is large enough to accommodate the tubular guide 55 and permit the head to slide backward and forward on this tubular guide 55. The lug 46 engages this head and slides in the slot 56. It will, therefore, be obvious that a retraction of the rod 45, by a manual retraction of the yoke formed by the cross bar 49 and the rods 50, will cause a retraction of this head 59 and as the shank 60 of this head is attached to the semi-cylindrical slide 18, a retraction of the rod 45 will cause a retraction of this slide 18 and a retraction of the breech block and this of course, bearing as it does against the forward end of the hollow head 32 of the firing pin, will cause a retraction of the firing pin to such an extent that the toothed end 35 of the firing pin will engage with the latch 41 and the parts will have the position illustrated in Fig. 5. The form of the head 59 with the shank 60 is illustrated particularly in Fig. 20 and it will be seen that this head 59 is laterally extended to one side of the plane of the shank 60 and is provided with a notch 62 which supports and guides the rear end of the firing pin rod 34. It will likewise be seen that after the end of the firing pin rod 34 has been engaged by the latch 42, the yoke formed by the cross bar 49 may be released and allowed to return under the action of the spring 54 and that this will return the slide 18 to its original position, as illustrated in Fig. 3, with the firing pin, however, retracted and in position to explode the cartridge upon an actuation of the trigger, whereby the latch 41 is raised from its engagement with the detent 35.

The trigger mechanism is illustrated in detail in Figs 4, 11 and 15 and in Fig. 2. As before stated, the rear end of the hollow head 32 is provided with a downwardly extending detent tooth 36 and engageable with this detent tooth is a sear 63. This sear is bifurcated at its forward end as at 64 and is mounted upon an arbor 65. The rear end of the sear is formed with a downward and rearward extension 66 having thereon a laterally projecting lug 67. Also pivoted upon the arbor 65 between the ears 68 of the sear is a lever 69 having a curved upper face 70 and a tooth 71 adapted to engage with a recess 72 formed in the forward end 125

of the sear. Operating against the curved face 70 of the lever 69 is a cam 73 whose under face is curved to conform to the curvature of the lever 69, this cam being mounted 5 upon a spindle or arbor 74, as shown in Fig. 4. Also mounted upon this arbor 74 at one extremity is a trigger 75 (see Fig. 2), this trigger being disposed upon the exterior of the metal housing formed of the sections 10 *a* and *b*. This trigger is normally covered or partially covered by a plate 76, as illustrated in Fig. 1, but the extremity 77 of the trigger projects beyond this plate and is formed with an enlarged thumb 15 piece. When the thumb piece 77 is depressed, the shaft or arbor 74 is rotated, which causes the rotation of the cam 73, and this in turn rotates the lever 69 until its tooth 71 engages with the sear above 20 its pivotal axis and rotates the sear in the direction of the arrow, Fig. 15, thus retracting the toothed extremity of the sear from its engagement with the detent 36. Also mounted upon the arbor 65, with its 25 ends disposed between the ears 68, is a member 79 which is upwardly and rearwardly curved and provided at its extremity with a laterally projecting lug 80 which engages against a shoulder 81 formed on the sear. 30 The opposite face of the member 79 is formed with a laterally projecting flange 82 and a spring 83 bears upward against this flange, one end of the spring being supported upon the stud 84, and the other bearing 35 against the upper edge of the forward end of the sear. This spring 83 acts to force upward the member 79 which thus, through its nose 80, acts to force upward the sear and urge the sear into position to be engaged by the detent 36. When, however, the trigger is operated, the free end of the sear will be depressed from its engagement 40 with the tooth 36 and the firing pin will be released. Means are also provided in connection with this trigger mechanism for preventing the explosion of the shell or cartridge unless the cartridge is firmly seated in the firing chamber. This means will be described later, however. 45

50 The latch 41 is a "safety" which normally prevents the projection of the firing pin after it has been retracted to its operative position and in order to provide means for shifting this "safety" to its inoperative position so as to permit the firing of the gun through the medium of the trigger, I mount in the lower portion of the hilt a longitudinally extending shaft 86. A portion of this shaft is enlarged and screw threaded as 55 at 87 and this enlarged screw threaded portion operates in a screw-threaded, longitudinally slideable, sleeve 88, as shown most clearly in Figs. 4 and 5 and Fig. 11. The forward end of the shaft is mounted in a supporting web 88', while the rear end of 60 the shaft passes through the member 57 and is engaged by a coiled spring 89, one end of which is fixedly attached to the member 57 by means of a pin or screw 90. The spring 89, therefore, acts to rotate this shaft 70 in one direction. The shaft 86 for a portion of its length is exposed upon the under side of the hilt which is cut away for the purpose as at 91 (see Fig. 1), and attached to this exposed portion of the shaft is a finger 75 piece 92. The spring normally acts to rotate the shaft so as to carry the finger piece to the left and against the under side of the hilt. The finger piece may be rotated by means of the fingers of the hand so as 80 to project to the right of the hilt and this action rotates the shaft 86 and shifts the sleeve 88 longitudinally along the shaft toward the rear thereof. The forward end of the sleeve is closed by a piece 93 which 85 carries upon it a flat longitudinally extended finger 94 (see Fig. 11) which finger, in the normal position of the sleeve, is disposed above the rear end of a safety latch 95, the forward end of which is bifurcated and 90 engaged with the pin 67 which projects from the downward extension of the sear 63, this latch 95 being pivoted intermediate of its ends. It will be seen that in order to retract the sear from its engagement with 95 the detent tooth 36 the extension 66 must be moved downward and this movement is prevented by the latch 95 unless the finger 94 has been withdrawn from engagement with this latch. The downwardly extending 100 rear end of the latch 95 is formed with a small recess 96 (see Fig. 13) within which the finger 94 is adapted to engage when the parts are in the positions shown in Figs. 4 and 5. Mounted upon the sliding sleeve 88 105 is a laterally and upwardly directed finger 97 whose upper and rear end is disposed in a vertical plane and which enters into a recess 98 formed in a pivoted member 99 which, as illustrated in Fig. 3, is pivoted at 110 100 and whose upper edge bears against the lug 44 which projects laterally from the latch 41. When the parts are in the position shown in Fig. 3 and in Figs. 4 and 5, the pivoted member 99 is depressed by the 115 spring 43 which holds the latch 41 in engagement with the tooth 35 on the firing pin. When, however, the shaft 86 is rotated in one direction by a rotation of the finger piece 92, the sleeve 88 will be shifted rearward, carrying with it the finger 97. This finger will enter the recess 98, thus shifting the pivoted member 99 or tumbler upward and raising the latch from its engagement 120 with the tooth 35 so as to permit the operation of the trigger 75 and the release of the firing pin through the medium of the trigger. 125

130 It will thus be seen that there are two "safeties" preventing the ordinary projec-

tion of the firing pin even after it has been retracted, one of these "safeties" being the member 95, and the other the latch 41, and that these safety locks can only be shifted

5 to an inoperative position by the rotation of the finger piece 92 and the holding of the finger piece in its shifted position by the grasp of the hand on the hilt of the sword. When this finger piece has been so shifted
10 and held it is then possible to fire the pistol as many times as desired by the actuation of the trigger, the recoil of the pistol acting to carry the breech block back to the position shown in Fig. 5 and again engage the tooth
15 36 with the extremity of the sear 63, the breech block being again shifted to its normal position, as shown in Fig. 4 or Fig. 3, by the actuation of the spring 54.

In order to prevent the accidental firing
20 of the gun when in its scabbard by pressure on the trigger, assuming that the setting yoke composed of the cross bar 49 and the rod 45 has been operated accidentally, I mount upon the exterior of the hilt a housing 101 within which is disposed, as illustrated in Fig. 2, a sliding bolt 102 which is impelled to a forwardly projecting position by means of a spring 103, this spring bearing at its forward end against a lug 104 and
25 at its rear end against the guard 78 of the trigger. The rear end of this bolt 102 is beveled and when the sword is placed within its scabbard, the end of the scabbard contacts with this bolt, and forces it rearward
30 so that it comes beneath the trigger, as illustrated in Fig. 2. When the bolt is forced beneath the thumb piece of the trigger, as in Fig. 2, it prevents the depression of the trigger by the thumb and the consequent firing
40 of the gun.

In order to provide for the ejection of the spent cartridge after firing, the side wall of the hilt just rearward of the forward end of the guard, as illustrated in Fig. 6, is formed
45 with an opening 105 normally closed by the imperforate wall of the slide 18. This slide, however, is formed with an ejection opening 105^a (see Fig. 8) and the wall of the slide carries a resilient strip 106, constituting a
50 retractor (see Fig. 24) formed with a small detent tooth 107 at its extremity which engages with the rim of the cartridge. Now when the slide is forced back by the recoil it carries the firing head back and carries
55 with it the retractor 106 and this carries back with it the cartridge. When the parts have reached the position shown in Fig. 5, a new cartridge is forced up into the firing chamber and this new cartridge displaces
60 the empty shell and forces it out through the openings 105 105^a.

In order to prevent the firing of a cartridge unless the latter is seated firmly in the firing chamber, I form the inner face of
65 the slide 18 rearward from the breech block

with a rib 108, this rib being formed with a projected portion 109 in its length. When the slide 18 has moved fully forward to the position shown in Figs. 3 and 4, the projection 109 or downward extension of the 70 rib 108 engages with the rounded upper face of the dog 79, and forces this dog downward, releasing the engagement between the lug 80 and the shoulder 81 on the sear 63 and this permits the manual actuation of 75 the trigger. If, however, the cartridge is not seated properly in the firing chamber, the slide 18 cannot return to its proper position and, as a consequence, the dog 79 is held up by the spring 83 (as in Fig. 22) and 80 the lug 80 engages with the shoulder 81, preventing the downward movement of the sear. A manual actuation of the sear is prevented by the fact that the dog 79 must be moved downward as well as the sear and 85 this dog 79 has a relatively long surface in contact with the spring 83 and, therefore, considerable power is required in order to flatten out the spring as well as shift the 90 sear.

It will be noted that the bed or cradle 17 is formed on its forward end with a solid portion 110 having a bore 111 into which the forward wall of the opening made for the reception of the upper end of the magazine frame engages. This forward wall is beveled as at 112 (see Fig. 5) and the rear wall of the bore is extended downward as at 113. The upper end of the magazine frame is formed with a tongue 114 which is 95 adapted to be inserted upward in front of the rear wall 113 and into the bore 111 and against the beveled face 112 of the extension 13 of the hilt. As shown in Fig. 3, the clip 100 24 is provided in its side walls with a plurality of openings 115 whereby the number of cartridges in the magazine may be determined and whereby it may be seen whether or not the magazine needs refilling. The forward end of one side wall of the slide 18 110 is extended as at 116 (see Figs. 7 and 8) so as to lie along and against the side face of the blade 10 and the lower edge of this extension is formed with a lug 117 constituting a seat for the projected end of the 115 barrel. The side walls of the slide, as shown in Fig. 7, and Fig. 9, are formed with grooves 118 engaging ribs 119 formed on the bed 17. This bed is, of course, rigid and attached to the frame of the hilt in any suitable manner.

It is to be understood that many of the details of construction may be changed if desired to suit the various exigencies of manufacture and I do not wish to be limited 125 to the manner in which the housing on the sword blade is constructed as it is obvious that this may be changed so as to permit the ready assembly or change of the mechanism within the housing without departing from 130

the spirit of the invention. While I have illustrated the frame holding the firing mechanism as made in two pieces, it is obvious that it might be made in one piece if 5 so desired.

The details of the operation have been heretofore described but the general operation may be recapitulated. Ordinarily the parts are in the position shown in Fig. 4, 10 no cartridge being in the barrel 14, and the firing pin being in its forward position. Now if it be desired to use the pistol, the rod 45 is retracted by means of the yoke until the firing pin 34 is engaged by the 15 latch 41 and the lug 36 on the firing pin has been engaged by the sear 63. The retraction of the firing pin and of the slide 18 permits a cartridge to be forced upward into the space in front of the breech block 20 and the release of the rod 45 causes the breech block to move forward with the parts in the position shown in Fig. 3. In this position the firing of the pistol is prevented until the finger piece 92 is shifted from its 25 position shown in Fig. 21 to an opposite position. This releases the safety latch 41 and then a pressure on the trigger 77 will release the sear and the spring 38 will cause the firing pin to be projected against the 30 cartridge. The recoil of the explosion will cause the slide 18 to move rearward together with the firing pin and the shell will be ejected in the usual manner while a new cartridge passes into the firing chamber. 35 The firing pin is caught by the sear but the slide returns to the position shown in Fig. 3 ready for firing the pistol again by another pressure on the trigger 77. If the last cartridge remains in the barrel unexploded and 40 a new magazine clip is inserted in the magazine holder or frame, there is no necessity of again retracting the rod 45. If, however, the last cartridge has been fired and automatically ejected, then in order to reset the 45 firing mechanism it is necessary to retract the rod 45. If the sword is returned to its scabbard with the firing pin in the position shown in Fig. 3 and a cartridge in the chamber, the pistol cannot be accidentally fired 50 because of the safety lock 102 which will be forced rearward and beneath the trigger 77, as shown in Fig. 2. As before stated, the pistol cannot be fired when the sword is in its scabbard unless the hilt is grasped and 55 the member 92 shifted against the force of the spring 89 and held in its shifted position by the grasp of the hand on the sword. Then the pistol may be fired by pressure upon the trigger. The pistol cannot be 60 fired, however, unless the cartridge is firmly seated in the barrel because of the mechanism illustrated in Figs. 22 and 23.

Having described my invention, what I claim is:

65 1. A sword having a hilt, a pistol barrel

mounted in the hilt, means whereby a cartridge may be deposited in the barrel, firing means disposed in the hilt, a trigger, and scabbard operated means for preventing the actuation of the firing means.

2. A sword having a hilt, a pistol barrel mounted in the hilt, firing means disposed within the hilt and including an exposed trigger having a laterally disposed thumb piece deppressible to release the firing mechanism, a housing, a sliding bolt mounted in the housing, a spring normally projecting the bolt away from the trigger and in position to be engaged by the scabbard, said bolt when engaged by the scabbard being forced 75 inward beneath the thumb piece of the trigger and preventing its actuation.

3. A sword blade having a hilt extending in line with the blade, a pistol barrel mounted in the hilt, firing mechanism disposed within the hilt, a safety lock preventing the actuation of the firing mechanism, and means for shifting the safety lock to an inoperative position comprising a member mounted upon the face of the hilt and shiftable 80 by the grip of the hand upon the hilt and when so shifted rendering the safety mechanism inoperative.

4. A sword having a hilt, a pistol barrel mounted in the hilt, firing mechanism disposed within the hilt, a safety lock preventing the actuation of the firing mechanism, and means for shifting the safety lock to an inoperative position comprising a member mounted upon the inside of the hilt shiftable 95 transversely thereto and when so shifted rendering the safety mechanism inoperative, said member being adapted to be held in this last named position by the grasp of the hand on the hilt.

5. A sword having a hilt, a pistol barrel mounted in the hilt, firing mechanism disposed within the hilt, a trigger, scabbard operated means for preventing the actuation of the firing means, means for locking the 110 firing mechanism from actuation, and a transversely shiftable member mounted upon the hilt which when shifted in one direction releases the last named locking means, the transversely shiftable member being adapted 115 to be held in a position to render the locking means inoperative by the grasp of the hand upon the hilt.

6. A sword having a hilt, a pistol barrel mounted on the hilt, firing means disposed 120 in the hilt and including a trigger, and a shiftable member disposed normally out of engagement with the trigger but adapted to be engaged by the scabbard of the sword and forced into engagement with the trigger to 125 prevent the actuation thereof.

7. A sword blade having a hilt extending in line with the blade, a pistol barrel mounted within the hilt, firing mechanism disposed within the hilt, a trigger, a magazine 130

- discharging into the hilt and behind the barrel and forming part of the guard of the hilt, means for manually and initially setting the firing mechanism, and means disposed on that portion of the hilt grasped by the hand normally preventing the actuation of the firing mechanism but permitting the actuation of the firing mechanism when the hilt is grasped and contracted on the hilt.
- 5 10. In a firearm, a hollow handle, a barrel engaged therewith, firing mechanism disposed within the hollow handle, and means for preventing the actuation of the firing mechanism unless the handle is grasped and including a pivotal transversely shiftable member mounted on the inner face of the handle adapted to be held in an inoperative position by the grasp of the hand on the handle.
- 15 20. 9. A sword having a hilt, a pistol barrel mounted in the hilt, firing mechanism disposed within the hilt, and including a manually operable trigger, and means for preventing the actuation of the firing mechanism unless the hilt is grasped, including a member disposed in a recess in the hilt, said member being pivotally mounted and yieldingly urged to a projected position beyond the face of the hilt, but shifted to an inoperative position within the face of the hilt by the grasp of the hand on the hilt.
- 25 30. 10. A sword having a hollow hilt, a guard, a pistol barrel mounted in the hilt, and firing mechanism disposed within the hilt and including a pivoted trigger having a thumb piece disposed upon one said face of the hilt and movable parallel to the adjacent face of the hilt.
- 35 40. 11. An arm having a hollow handle, a pistol barrel mounted therein, a breech block disposed within the hollow handle, a spring actuated firing pin mounted in the breech block, manually operable means for retracting the breech block and the firing pin from the barrel, the extremity of the firing pin being formed with a detent, a trigger operatively engaging the firing pin and holding it in a retracted position, a latch disposed within the handle and adapted to engage the detent on the firing pin to hold the pin retracted, and manually operable means on the handle for shifting the latch from its engagement with the firing pin whereby the trigger may then be operated to release the firing pin.
- 45 50. 12. A sword having a hollow hilt, a pistol barrel mounted therein, a slide carrying a breech block disposed in the hilt behind the barrel, a spring urging the breech block to closed position, a spring actuated firing pin mounted in the breech block, means for manually retracting the slide and the firing pin, means for holding the firing pin in retracted position, a trigger operated means 55 for releasing the last named means, addi-
- tional means for holding the firing pin in retracted position, and means on the hilt shiftable by the hand into position to release said second named holding means.
- 60 65. 13. A sword having a hollow hilt, and a guard, a pistol barrel mounted in the hilt, a slide mounted in the hilt and carrying a breech block movable toward and away from the barrel, a spring urging the slide with the breech block against the barrel, a firing pin mounted in the slide and having an extension formed with a tooth, a spring urging the firing pin through the breech block, a trigger releasable sear engageable with the firing pin to hold it in its retracted position, a safety lock engageable with the toothed extension of the firing pin, and means mounted on the hilt of the sword facing the guard whereby to release said last named safety lock.
- 70 75. 14. In a firearm, a hollow handle, a barrel, a slide carrying a breech block movable toward or from the barrel, a spring urging the slide against the barrel, a firing pin carried by the slide, a spring urging the firing pin into operative position, said firing pin having an extension formed with a tooth, a trigger actuated sear engageable with the firing pin, a rotatable shaft mounted in the handle and having a member projecting therefrom upon the inner face of the handle and adapted to be rotated and held in its rotated position by the grasp of the hand on the handle, mechanism actuated by the rotation of said shaft acting to release the pivoted locking member from its engagement with the firing pin extension, and means for manually retracting the slide and the firing pin to carry the latter into engagement with the pivoted locking device.
- 80 85. 15. A sword having a hilt, a pistol barrel mounted in the hilt, firing mechanism disposed in the hilt and including a trigger, and means for preventing the operation of the firing mechanism unless the hilt is grasped and including a shaft extending along the inner face of the hilt, a spring urging the shaft in one direction, and a radially projecting member mounted on the shaft and exposed upon the face of the hilt and adapted to be transversely and rotatably shifted by the hand on the hilt and held in its shifted and inoperative position against the force of the spring.
- 90 95. 16. In a firearm, a bed piece having a plurality of transverse grooves open at one end, a barrel having ribs upon its rear end engageable with said grooves and thereby engaged with the bed, a slide having sliding engagement with the bed piece and carrying a breech block engageable with the rear end of the barrel, a guide mounted upon the rear end of the bed piece, a firing pin having its forward end mounted within the breech block and having a rearward extension pass-
- 100 105. 110 115. 120 125. 130

ing through said guide on the bed piece, a spring urging the firing pin into a projected position, means for retracting the firing pin and slide, and a trigger releasable means for holding the firing pin in its retracted position.

17. A sword having a hollow hilt, a pistol barrel mounted therein, a slide partly surrounding the barrel and movable through the hilt and formed with a breech block, a spring urging the slide to a position with its breech block against the rear end of the barrel, a firing pin mounted in the breech block and normally projecting therethrough, a spring urging the firing pin to a projected position, means for manually retracting the slide and firing pin, trigger releasable means for retaining the firing pin in its retracted position, but permitting the forward movement of the breech block relative to the firing pin, a magazine forming part of the sword guard and discharging into the space between the breech block and the barrel when the breech block is retracted, means in the magazine for urging cartridges into said space when the breech block is retracted, and means for extracting the spent cartridges.

18. A firearm having a hollow handle, a barrel mounted on the forward end of the handle, a recoil operated slide mounted in and longitudinally movable through the handle and formed with a breech block, a firing pin mounted in the breech block and normally projecting therethrough, a spring urging the slide into position with its breech block against the rear end of the barrel, a spring urging the firing pin to its projected position, manually operable means for initially retracting the slide and firing pin, trigger releasable means for holding the firing pin in its retracted position, but permitting the projection of the breech block, and a safety lock engageable with the firing pin when it is retracted and preventing the projection of the firing pin but manually releasable by the action of the trigger to permit the projection of the firing pin.

19. A firearm including a hollow handle, a barrel, a recoil operated slide mounted within the hollow handle and formed with a breech block, a spring urging the breech block against the barrel, a firing pin mounted in the breech block and normally projecting therethrough, a spring urging the firing pin to its projected position, a trigger releasable means for holding the firing pin in its retracted position, and means preventing the release of said holding means until the slide has moved snugly against the end of the barrel.

20. A firearm including a hollow handle, a barrel, a recoil operated slide mounted within the hollow handle and including a breech block, a spring urging the slide

against the barrel, a firing pin mounted in the slide and normally projecting therethrough, a spring urging the firing pin to its projected position, a trigger releasable means for holding the firing pin in its retracted position, means preventing the release of said holding means until the slide has moved snugly against the end of the barrel and including a member carried by the slide, a locking device operating in connection with the trigger operated mechanism shifted into operative position by a retraction of the slide but released from its operative position by the movement of the said slide and the said member forward to its full extent.

21. A sword having a hollow hilt, a housing forming part of the hilt and disposed on one side of the sword blade, a barrel mounted in the housing, a bed upon which the barrel is mounted and extending rearward from the barrel, a slide partly surrounding the barrel and slidably mounted upon the bed and having a tubular breech block, a firing pin mounted in the tubular breech block and having a rearward extension, a spring bearing at one end against a projection on the bed and at the other end bearing against the firing pin and urging it to a projected position, a slide retracting rod extending longitudinally through the hilt to the butt end thereof and operatively connected to the slide, a spring acting to shift the rod and slide to its projected position, a yoke connected to the rod and disposed at the butt end of the hilt whereby the rod and the slide may be retracted to initially set the firing mechanism, a sear engaging the firing pin when the slide and firing pin are retracted and holding the firing pin in its retracted position, a trigger mounted upon the hilt adjacent the guard and depressible by the thumb, an intermediate mechanism actuated by the trigger for releasing the sear to permit the projection of the firing pin.

22. A combined sword and pistol, the sword having a hollow hilt, the pistol barrel being mounted in the hilt, a breech block mounted in the hilt and shiftable rearward by the recoil, a spring urging the breech block against the barrel, a spring actuated firing pin mounted in the breech block, a trigger releasable sear engageable with the firing pin when the latter is retracted and holding it retracted while the breech block moves forward, and means for initially retracting the breech block and thereby the firing pin.

23. A combined sword and pistol, the sword having a hollow hilt, the pistol barrel being mounted in the hilt, a breech block mounted in the hilt and shiftable rearward by the recoil, a spring urging the breech block against the barrel, a spring actuated

- firing pin mounted in the breech block, a trigger releasable sear engageable with the firing pin when the latter is retracted, means for initially retracting the breech block and 5 the firing pin, means for locking the firing pin in its retracted position, and manually operable means disposed on the inside of the hilt for releasing said last named locking means.
- 10 24. A combined sword and pistol, the sword having a hollow hilt, the pistol barrel being mounted in the hilt, a breech block mounted in the hilt and shiftable rearward by the recoil, a spring urging the breech block against the barrel, a spring actuated 15 firing pin mounted in the breech block, a trigger releasable sear engageable with the firing pin when the latter is retracted, means for initially retracting the breech block and 20 the firing pin, means for locking the firing
- pin in its retracted position, manually operable means disposed on the inside of the hilt for releasing said last named locking means and including a rotatable shaft having a radially projecting member exposed 25 upon the inner face of the sword hilt, a screw threaded member carried by the shaft, a longitudinally movable slide with which the screw threaded member engages, and a finger projecting from the slide and when 30 retracted operatively engaging said locking device to lift it and release it from its engagement with the firing pin.
- In testimony whereof I hereunto affix my signature in the presence of two witnesses. 35

JOHN KRASNODEMSKI.
